UNITED STATES PATENT OFFICE.

NORBERT SCHREIBER AND RAPHAEL ROSENTHAL, OF LINCOLN, ILLINOIS.

BOILER-SKIMMER.

1,165,717.

Specification of Letters Patent. Patented Dec. 28, 1915.

Application filed October 17, 1914. Serial No. 867,055.

To all whom it may concern:

Be it known that we, NORBERT SCHREIBER and RAPHAEL ROSENTHAL, citizens of the United States, residing at Lincoln, in the county of Logan and State of Illinois, have invented a certain new and useful Improvement in Boiler-Skimmers, of which the following is a full, clear, concise, and exact description, reference being had to the accompanying drawings, forming a part of this specification.

Our invention relates to boiler skimmers for skimming or taking off the scum or refuse matter on top of the water in the boiler.

Prominent objects of the invention are to provide a simple and practical construction of device of the class mentioned; to simplify the same, reducing the number of parts to a minimum and making the construction inexpensive; to provide simple and expeditious means for withdrawing and disposing of the skimmed matter; to provide a form of device particularly adapted for use in locomotive boilers; to arrange for the advantageous use of the skimmed matter in assisting the traction efforts of the locomotive; and to secure the foregoing and other desirable results in a simple and expeditious manner.

In carrying out our invention in the manner herein set forth, we provide a suitable frame conveniently made of pipes or pipe sections connected together and supported by attached floats, whereby said frame may easily rest or float upon the surface of the water which is to be skimmed. This frame has suitable apertures or openings to permit the entry into it of the skimmed matter which apertures or openings form a suitable surface intake. A convenient arrangement is to have the sides of the pipes provided with apertures or openings in the form of circular holes, although of course this arrangement of surface intake could be varied. The floating frame is connected by a loose or movable connection with a suitable outlet pipe, whereby the skimmed matters may be withdrawn and discharged.

As a further improvement the frame may be made of substantially rectangular and oblong form so as to fit into the rear upward portion of a locomotive boiler, one end of the frame being elevated so as to pass over the top of the dry pipe of the boiler, and the outlet or discharge end of the device may be

conveniently connected with the throttle valve of the locomotive whereby the discharge may be regulated by the throttle.

As a matter of further and specific improvement the discharge is directed upon or against the track on which the locomotive runs between the driving wheels thereof, whereby the traction of the locomotive may be increased.

In the accompanying drawings Figure 1 is a plan of a boiler skimmer embodying our present invention; Fig. 2 is a side elevation of the same; Fig. 3 is an end elevation of the device; Fig. 4 is a view of a portion of a locomotive boiler showing our improved skimmer embodied therein; Fig. 5 is a horizontal section of a portion of the device showing certain details of construction more fully.

Referring first to Figs. 1, 2 and 3, we show a frame A which is preferably made of general rectangular form as shown in Fig. 1. Said frame is desirably made of pipe sections as 1, 2, 3, 4—4 and 5—5, sections 5—5 being vertical and supporting the elevated sections 4—4, which are connected by coupling 6. The outer sides of the pipes 1, 2 and 3 are preferably provided with apertures or openings 7 (Figs. 2 and 5), so as to provide a surface intake for the refuse or scum to be skimmed off the top of the water.

Fleats 10—10 are provided to support the frame A. Preferably four floats 10 are employed, conveniently located at or about the corners of the frame A as shown in Fig. 1. These floats may be arranged or connected in any suitable way so as to support the frame A, a convenient arrangement being that shown in the drawings wherein side pipes 11—11 are provided and the floats 10 mounted upon them, each float having a threaded connection, as shown at 12 with the pipe 11 whereby it may be adjusted with reference to said pipe. The side pipes 11 are supported by small cross pipes 14—14 connected to the main pipes 1—1. The floats 10 are preferably elongated as shown in the drawings, whereby they may be arranged close to the frame A.

An outlet pipe 15 is connected by a T-shaped coupling 16 with the pipe 2, the coupling 16 being preferably loose so as to give it a rotary or swivel connection with said pipe 2. Said pipe 15 is connected at its other end to another T 17, which is mounted

loosely upon a short pipe section 18 (Fig. 5) connected by a yoke 19 with a pipe 20. The coupling 17 is also mounted for rotation or swivel movement upon the pipe section 18, whereby an up down movement of the frame A is permitted by the outlet connection 15, the ends of the pipe 18 being conveniently closed by plug caps 21. The pipe 20 may be any suitable discharge pipe extended to any desired locality to effect a proper discharge of the refuse matter skimmed from the top of the water.

The construction just described is particularly advantageous for use in a locomotive boiler and is so shown in Fig. 4. In such case elevated pipes 4—4 are located above the dry pipe 23 of the locomotive, a portion of whose boiler 24 is shown in the drawings, the frame A being of suitable size 20 to fit conveniently within the rear of said boiler, as shown. In this case the outlet pipe 20 is desirably extended back to the rear of the locomotive and provided with a valve 25 having a link and lever connection 26 and 27 with the throttle lever 28, whereby the discharge through the pipe 20 may be controlled by the throttle. When the lever 28 is operated to open the throttle valve, the valve 25 is opened so as to permit 30 a discharge from the skimmer and when the lever 28 is operated to close the throttle, the valve 25 is also closed, whereby there is a continuous blow-off from the skimmer while the engine is running, or at least while it is 35 receiving steam for operation.

As a matter of further improvement we show a supplemental discharge pipe 29 leading down almost to the track 30 on which the locomotive runs between the driving 40 wheels thereof. In this way the refuse matter from the boiler may be discharged upon the track and so help the traction of the engine. The pipe 29 is preferably provided with a separate hand valve 31 by which discharge through said pipe 29 may be further 45 controlled.

It will be understood that changes and modifications may be made without departing from the spirit of the invention. It 50 is also understood that the elevated pipes 4—4 are particularly intended for use in a locomotive boiler and that when the device is used for other purposes said end pipes would preferably not be elevated but would 55 be in more or less the same plane with the pipes 1, 2 and 3. It will be seen that by making the device of pipe sections in this way great economy and expediency in manufacture are secured, because no special fittings, casings or patterns are required, pipe 60 sections of standard pipe being used.

What we claim as our invention is:

1. A device of the class specified comprising a rectangular frame made of side and 65 end pipe sections, one or more of which

sections are provided with surface intake openings, in combination with other pipe sections extending lengthwise alongside of the sides of said frame and connected to the latter, and floats mounted upon said other 75 pipe sections and adjustable longitudinally thereof.

2. A device of the class specified comprising a frame made of pipe sections connected together and provided with surface intake 75 openings, the pipe sections at one end of the frame being elevated and connected with the remaining pipe sections by vertically extending side pipe sections, and floats carried by the first mentioned pipe sections. 80

3. A device of the class specified comprising a frame made of pipe sections connected together and provided with surface intake openings in combination with floats arranged at the corners of said frame and connected therewith, said floats being mounted upon side supports connected to said frame, said side supports comprising pipe sections extending alongside of the pipes forming 85 said frame. 90

4. A device of the class specified comprising a rectangular frame made of side and end pipe sections, one or more of which sections are provided with surface intake openings, in combination with other pipe sections 95 extending lengthwise of the sides of said frame and connected to the ends thereof, and floats mounted upon said other pipe sections. 100

5. The combination with a locomotive boiler, of a skimming device arranged there-in and provided with intake openings, and a mechanical connection between the locomotive throttle lever and the valve controlling the discharge from the skimmer, whereby said valve is opened when the throttle lever is actuated to open the throttle valve and also whereby said discharge valve is closed when said lever is actuated to close 105 the throttle valve. 110

6. The combination of a tubular device 110 made in the form of a frame and provided with a surface intake, of float supports connected with said tubular device and extending along one or more of the sides thereof, and elongated floats mounted upon said supports. 115

7. The combination with a locomotive boiler of a tubular frame having a lower portion provided with a surface intake and having an elevated portion adapted to extend over the top of the dry pipe of said boiler, floats on the lower portion of said frame, and an outlet pipe having a connection with said frame adapted to permit movement of said frame in accordance with 120 changes in the water level. 125

8. The combination with a locomotive engine boiler, of a device for removing refuse from the water in the boiler comprising a tubular structure provided with a surface 130 135

intake and supporting floats, a throttle lever and means whereby said throttle lever controls the discharge from said skimming device.

5 9. A device of the class specified comprising a frame composed of side and end tubular members whereof the side members are provided along their length with intake openings, and floats mounted upon supports 10 consisting of members extending lengthwise alongside of said side members of said frame.

10 10. A device of the class specified comprising a frame composed of side and end tubular members, whereof the side members are provided along their length with intake 15 openings, floats mounted upon supports consisting of members extending lengthwise alongside of said side members of said frame, and a connection for permitting the 20 rise and fall and also the surface movement of said frame comprising an inextensible member pivotally connected to one end of said frame and pivotally supported at its 25 other end, so as to give a double pivoted or hinged connection with said frame.

11. A device of the class specified comprising in combination a frame composed of relatively long side tubular members and 30 relatively short end members connecting the same, whereof the side members are provided along their length with surface intake openings, one of said members being tubular and communicating with the tubular side 35 members, float supporting members extending lengthwise alongside of said side members and connected with the latter near the ends thereof, elongated floats carried by 40 said float supporting members and extended longitudinally of the same, and an outlet connection with said tubular end member, said connection being adapted to permit the 45 rise and fall of said frame and also to permit the movement thereof in a direction longitudinally of said side members.

12. A device of the class specified comprising in combination a frame composed of relatively long side tubular members and relatively short end members connecting the 50 same, whereof the side members are provided along their length with intake openings, one of said end members being tubular and communicating with the tubular side members, float supporting members extending 55 lengthwise alongside of said side members and connected with the latter near the ends thereof, elongated floats carried by said float supporting members and extending longitudinally of the same, and an outlet connected with said tubular end member, said outlet being adapted to permit the rise and 60 fall of said frame and also to permit the movement thereof in a direction longitudinally of said side members, said outlet comprising a single inextensible pipe section

having a swivel connection with said tubular end member and communicating therewith, and an outlet pipe with which the other end of said pipe section is pivotally connected.

70 13. A device of the class specified comprising in combination, a frame made of tubular members provided with surface intakes, said frame being free to rise and fall with variations in the water level and also free to move horizontally on the water surface, floats carried by said frame, and an outlet connection for said frame, said connection comprising a single inextensible pipe section having one end pivotally connected with said frame, and an outlet pipe to which the other end of said pipe section is pivotally connected.

75 14. The combination with a locomotive boiler, of a tubular frame comprising side and end members whereof the side members are provided with surface intakes substantially throughout their entire length, one end of said frame being tubular and connected with said tubular sides and provided with a tubular outlet connection adapted to permit the bodily upward and downward movement of said frame, and also the longitudinal adjustment thereof, and the other end of said frame being provided with 80 upwardly extending side members and an end member extending between the same, said end member being sufficiently elevated to lie in position above the dry type of the boiler for varying heights and longitudinal 85 adjustments of said frame, and floats for said frame.

90 15. The combination with a locomotive boiler, of a skimming device therefor comprising a frame having longitudinally extending tubular side members provided throughout substantially their entire length with surface intake openings, said frame having at one end an elevated end member adapted to be positioned above the boiler 95

100 dry pipe for various heights and longitudinal adjustments of said frame, the other end of said frame being tubular and connected with said tubular side members, an outlet for said frame comprising a pipe section 105 pivotally connected with said tubular end of said frame, a discharge pipe having one end pivotally connected with said pipe section, said discharge pipe being provided with a valve to control the discharge from the 110 skimmer, a throttle lever and mechanical connections between said throttle lever and said valve whereby the latter is actuated to open and close the skimmer discharge pipe by the movement of the throttle lever to 115 open and close the throttle valve.

120 16. A device of the class specified comprising a frame having a plurality of longitudinally extending separated members provided along their length with surface 125

intake openings, a tubular cross member connecting said longitudinally extending members, and an outlet connected with said cross member and adapted to permit the rise 5 and fall of said frame and also the movement of the same over the surface of the water, and floats carried by said frame.

17. A device of the class specified comprising a frame having a plurality of longitudinally extending separated members provided along their length with surface intake openings, a tubular cross member connecting said longitudinally extending members, and an outlet connected with said cross member and adapted to permit the rise and fall of said frame and also the movement of the same over the surface of the water, and floats carried by said frame, said outlet comprising an inextensible pipe section pivotally connected to said cross member and an outlet pipe to which said pipe section is pivotally connected.

18. A device of the class specified comprising a frame having a longitudinally extending tubular member provided along its length with surface intake openings, floats at the opposite ends of said tubular member, and an outlet connection connected with one end of said tubular member and adapted to permit the rise and fall of said member with changes in the height of the water level, and also adapted to permit longitudinal movement of said member upon the water surface.

19. A device of the class specified comprising a frame having a longitudinally extending tubular member provided along its length with surface intake openings, floats at the opposite ends of said tubular member,

and an outlet connection connected with one end of said tubular member and adapted to permit the rise and fall of said member with changes in the height of the water level, and also adapted to permit longitudinal movement of said member upon the water surface, said outlet including a pipe section having pivotal connections at both ends.

20. A device of the class specified comprising a quadrilateral frame whereof two opposite sides are provided along their length with surface intake openings, floats at substantially the corners of said frame, and an outlet connected with said frame and adapted to permit the rise and fall of the same in accordance with changes in the height of the water level, and also adapted to permit horizontal movement of the frame upon the surface of the water.

21. A device of the class specified comprising a frame having a longitudinally extending tubular member provided along its length with surface intake openings, floats at the opposite ends of said member, a laterally extending tubular member at one end of said longitudinally extending member, and an outlet connection including a pipe section pivotally connected to said laterally extending member, and also including an outlet pipe to which said pipe section is pivotally connected.

In witness whereof, we hereunto subscribe our names this 8th day of October, A. D. 1914.

NORBERT SCHREIBER.
RAPHAEL ROSENTHAL.
